[57] CLAIM

The ornamental design for a telephone handset and cradle, as shown and described.

DESCRIPTION

FIG. 1 is a perspective view of the telephone handset of the present invention while resting in the cradle of the present invention, showing my new design;

FIG. 2 is a top view of the telephone handset of the present invention resting in the cradle of the present invention;

FIG. 3 is a side view of the telephone handset resting in the cradle, wherein an opposite side view of the telephone handset and cradle is substantially a mirror image thereof;

FIG. 4 is a view of the bottom of the telephone handset;

FIG. 5 is a bottom view of the cradle;

FIG. 6 is a top view of the cradle. The handset and cradle have been shown separately in (FIGS. 4-6) for convenience of illustration;

FIG. 7 is a left end view of the telephone handset resting in the cradle; and

FIG. 8 is a right end view of the telephone handset resting in the cradle.
